UNITED STATES PATENT OFFICE.

FRED S. CARR, OF NEWTON, MASSACHUSETTS, ASSIGNEE TO CARR FASTENER COMPANY, OF CAMBRIDGE, MASSACHUSETTS, A CORPORATION OF MAINE.

FASTENER.

Application filed July 22, 1925. Serial No. 45,265.

This invention aims to provide improvements in separable fasteners.

In the drawings, which illustrate a preferred embodiment of my invention:—

5 Fig. 1 is an elevation view of the fastener shown in connection with securing together the overlying portions of any flexible material;

10 Fig. 2 is a section on the line 2—2 of Fig. 1;

15 Fig. 3 is a section on the same line as Fig. 2, but showing the stud and socket partly engaged;

20 Fig. 4 is an elevation view of the stud-engaging part of the socket secured to its support;

25 Fig. 5 is a side elevation of the resilient stud-engaging part; and

30 Fig. 6 is a plan view of the stud-engaging part showing the attaching prongs.

Referring to the drawings, I have shown a socket having a stud-engaging part or casing 1 made in one piece and providing an outer wall 2 from which extend a plurality of attaching prongs 3. The casing 1 is also provided with a stud-receiving aperture 4 surrounded by a generally curved wall 5 of substantial width for engagement with the neck of a stud and contributing to the strength of the stud-engaging part without impairing the resiliency thereof.

To permit expansion and contraction of the casing 1, a slot 6 is provided, which extends from the stud-receiving aperture 4 through the outer wall 2. Thus the socket casing 1 may be expanded and contracted "as a whole" when engaging or disengaging a stud.

The socket may be secured to any suitable support, but it is herein illustrated as secured to a flexible carrying medium 7, which may be cloth, leather or the like. A cap member or attaching plate 8 is provided at the opposite side of the carrying medium 7 from the casing 1 and is provided with means for receiving and upsetting the prongs 3 after having passed through the carrying medium as illustrated in Figs. 2 and 3. The means for receiving the prongs 3 comprise an annular anvil portion 9 generally curved in cross-section, and an inwardly turned flange portion 10 against which the ends of the prong finally rest to prevent axial movement of the cap relative to the casing after once having been secured to the carrying medium. The

anvil portion 9 is made relatively wider in cross-section than the anvil portion of a cap used in connection with a socket wherein the casing part is not expansible and contractible as a whole, so that the attaching prongs may 60 turn quickly after striking the anvil portion 9 and bend outwardly and downwardly against the flange portion 10 and not follow the general contour of the anvil portion. Thus the combination of this attaching means 65 with a socket, the casing of which is expansible and contractible as a whole, is particularly advantageous in that the attaching prongs 3 and their engagement with the carrying medium 7 and the cap member 8 do not 70 to any appreciable extent interfere with the contraction and expansion of the stud-engaging part 1.

As the casing expands and contracts for engagement with or disengagement from a 75 stud, the flexibility of the carrying medium together with the annular space 11 between the upset ends of the attaching prongs and the outer rim of the cap permit the attaching prongs 3 to shift laterally with the casing 1 80 relative to the cap 8, as best illustrated in Fig. 3.

The cap 8 is provided with a central dome-shaped portion 12, which strengthens the cap materially and at the same time provides a 85 recess into which the carrying medium may be displaced by the head of a stud when the socket is engaged therewith, as illustrated in Fig. 2. The socket, including the attaching part 8, is relatively thin and very strong and 90 therefore is peculiarly adapted for use on frocks, overalls and the like which have to be laundered. It is adapted to withstand the rough usage that it receives from the laundry machinery without being injured to the extent of interfering with its operation.

The stud, as illustrated, is pressed from a single piece of metal and presents a ringlike head 13, a neck 14 and a base portion 15 secured to a flexible carrying medium 16 by a 100 rivet 17. The rivet includes a base flange 18 located at the opposite side of the carrying medium from the stud and the tubular part of the rivet passes through the carrying medium 16 and is upset in a depression 19 in 105 the head 13 of the stud, thereby gripping the carrying medium between the base 15 of the stud and the base flange 18 of the rivet, as illustrated in Figs. 2 and 3.

Separation of the stud and socket may be 110

readily effected by lifting one edge of the carrying medium adjacent the socket, thereby causing the casing 1 to be expanded by the camming action of the generally curved 5 wall 5 against the side of the stud to permit the socket to tip out of engagement with the stud.

The claims of this application are intended to cover broadly all similar applications filed 10 by applicant on the same date as this application. Some of the claims read on all of the applications, while others read only on those other applications which show the combinations claimed. However, this application 15 does not contain specific claims to any of the particular structures shown in the other applications where those structures and combinations differ from the fastener shown and described in this application.

20 While I have shown and described a preferred embodiment of my invention, it will be understood that I have done so for purposes of clarification rather than limitation, my invention being best defined in the appended claims.

Claims:

1. A separable fastener socket comprising, in combination, a one-piece slit stud-engaging part having a stud-receiving aperture 30 adapted to be enlarged by lateral expansion of said stud-engaging part as a whole, a cap part located at the opposite side of a socket-carrying support from said stud-engaging part and means presented by one of said 35 parts for engagement with the other of said parts for securing them to the support while permitting contraction and expansion of said stud-engaging part without any substantial interference from said cap or the support.

40 2. A separable fastener socket comprising, in combination, a stud-engaging part slit across one side to permit expansion and contraction of said part as a whole for engagement with or disengagement from a stud, a 45 cap part and a plurality of attaching prongs presented by said stud-engaging part for engagement with said cap to secure said stud-engaging part and said cap to opposite sides of a suitable support without any substantial 50 interference with the expansion and contraction of said stud-engaging part.

55 3. A separable fastener socket comprising, in combination, a split stud-engaging part expandable and contractible as a whole to permit engagement thereof with a stud, a cap part and a plurality of attaching prongs presented by said stud-engaging part for engagement with said cap to secure said stud-engaging part and said cap to opposite sides 60 of a suitable support, said attaching prongs shiftable with said stud-engaging part relative to said cap and the support to facilitate expansion and contraction of said stud-engaging part.

65 4. A separable fastener socket comprising,

in combination, a split stud-engaging part having a stud-receiving aperture there-through, a plurality of attaching prongs presented by said stud-engaging part and a cap presenting means for upsetting said prongs after passage through a support to secure said cap and said stud-engaging part to opposite sides of the support, and means co-operating to permit lateral movement of said prongs relative to said cap during expansion 75 and contraction of said stud-engaging part when engaging or disengaging a stud.

5. A one-piece resilient fastener element expandable and contractible as a whole in a single lateral plane, a plurality of attaching 80 prongs extending therefrom for securing said element to a support, said prongs being expandable and contractible with said fastener element, and a prong-receiving part located at the opposite side of a fastener support, 85 said prong-receiving part presenting means for upsetting and clenching said prongs while permitting shifting movement of said prongs during expansion and contraction of said fastener element.

90 6. A fastener socket including a split stud-engaging part presenting a plurality of attaching prongs at the periphery thereof, a prong-receiving part at the opposite side of a flexible support through which said prongs pass to engage said prong-receiving part and secure said casing to the support, said part and said prongs shiftable laterally as a whole relative to said prong-receiving part and the flexible support to permit 100 engagement of said casing with a stud.

95 7. A separable fastener element comprising, in combination, a resilient body portion contractible and expandable as a whole for engagement with a cooperating fastener element, an attaching cap at the opposite side of a carrying medium and attaching means passing through the carrying medium and securing said cap and said body portion to the carrying medium, said attaching means 110 being adapted to yield when said body portion is expanded or contracted.

115 8. A fastener socket comprising, in combination, a one-piece stud-receiving element presenting a ring having upturned inner and outer flanges and a relatively narrow face portion between said flanges, said ring slotted to permit expansion thereof during entrance and removal of the stud, the portion of said stud-receiving element connecting said inner wall and said face portion, curved to present a stud-guiding cam surface to facilitate entrance of the stud and expansion of the stud-receiving element during entrance 120 of the stud, and attaching prongs integral 125 with said stud-receiving element and attaching means on the opposite side of the socket-carrying medium for engagement by the ends of said prongs.

130 9. A fastener socket comprising, in com-

bination, a one-piece stud-receiving element presenting a ring having upturned inner and outer flanges and a relatively narrow face portion between said flanges, said ring slotted to permit expansion thereof during entrance and removal of the stud, the portion of said stud-receiving element connecting said inner wall and said face portion, curved to present a stud-guiding cam surface to facilitate entrance of the stud and expansion of the stud-receiving element during entrance of the stud, and attaching prongs integral

with said stud-receiving element and attaching means on the opposite side of the socket-carrying medium for engagement by the ends of said prongs, the plane of the face of said attaching means adjacent the socket-carrying medium spaced a substantial distance from the plane of that face of said flanges adjacent the socket-carrying medium. ¹⁵ ₂₀

In testimony whereof I have signed my name to this specification.

FRED S. CARR.
